UNITED STATES PATENT OFFICE.

ERNEST P. PARSONS, OF CLEVELAND, OHIO; WILBUR M. BALDWIN, ADMINISTRATOR OF SAID ERNEST P. PARSONS, DECEASED, ASSIGNOR TO THE PARSONS & PARSONS COMPANY, OF CLEVELAND, OHIO.

WEARING APPAREL.

Application filed April 12, 1926. Serial No. 101,274.

My invention relates to wearing apparel, particularly neckwear or a collar made of celluloid or equivalent material which is stiffly flexible. In general my object is to provide a celluloid collar having separate buttonhole tabs affixed to the band thereof in a simple and durable manner by means of a tongue connection. A further object of my invention is to provide a freely flexible tab which will permit convenient buttoning of the collar and avoid breakage of the stock or rupture at the union between the parts.

In the accompanying drawing, Fig. 1 is a perspective view of a collar embodying my improvement. Fig. 2 is an inner view, enlarged, of a portion of the collar and one buttonhole tab affixed thereto. Figure 3 is a horizontal section of the collar and tab on line 3—3 of Fig. 2. Fig 4 is a view of the inner side of the collar with the tab removed, and Fig. 5, is a perspective view of the tab. Fig. 6 is a sectional view of the tab on line 6—6 of Fig. 5. Fig. 7 is an inner view of a modified form of the invention in which the locking tongue is an integral part of the collar band. Fig. 8 is a sectional view of the collar and tab on line 8—8 of Fig. 7, and Figs. 9 and 10 show the same collar and tab separated. Fig. 11 is an inner view of another form of the invention, and Fig. 12 is a sectional view thereof on line 12—12 of Fig. 11, while Figs. 13 and 14 show the same collar and tab separated.

35 The collar shown in the drawings is of the lay down or folded type, having an outer or visible fold 2 and an inner band 3. Customarily the band is extended beyond the
40 end edges of the outer fold to provide integral buttonhole tabs, but in the present instance the band terminates approximately opposite the end edges 4—4, and the tabs
45 5—5 are separate pieces of the same material as the main body or of thinner and more flexible material to promote buttoning operations at the buttonholes 6—6. Each tab 5
50 is secured to band 3 without the use of separate fastening devices, except cement. Thus, each tab 5 is elongated and made narrower at its inner end to permit it to be inserted between the outer fold 2 and band 3 with the upper edge 8 of the tab placed relatively near the bend or folded corner

9 of the collar and slanting upwardly. The inner end of the tab is provided with a tongue 10 which is punched out and bent to lie at one side of the plane surface or stock itself near the end edge of the tab and rearwardly of button hole 6. The tongue 10 may extend forwardly as shown in Figs. 1 to 6, and have hook engagement with band 3 which is provided with a narrow vertical slot 11 to receive the tongue. When the tab is connected to the band in that manner the tongue projects through slot 11 and lies flat against the inner surface of band 3, where it may be cemented to the band and prevented from disengaging itself. The meeting faces of the tab and band may also be cemented together in part or wholly wherever engaged, thus fixing the tab at any desired slant or in any predetermined position at the end edges of the collar. The hook connection and the cemented union supplement each other in resisting the end pull or stresses in attaching the collar to a shirt and when the collar is being used; the cemented union also maintains the alignment of the tab under strain. The tab may extend a considerable distance beyond the end edges 4 of the collar to permit the tab to be flexed easily, and such flexure and the buttoning of the collar is further promoted by cementing the tab to band 3 only in the area of tongue 10. In that connection it must be understood that celluloid, or so-called celluloid stock made to resemble linen, is of springy character and not as flexible as a starched linen collar and may be cracked if bent sharply. The tabs are therefore made separate and attached as described to promote the life of the collar where attachments must be made to the shirt, and in Fig. 1 I show a horizontal slot 12 in band 3 above the rear buttonhole 14 to permit the band to be easily flexed in buttoning operations.

In Figs. 7 to 10 I show a modified form of the invention, the band 15 of the collar being made with a tongue 16, and the tab 17 having the slot 18 for receiving the tongue. In this form of the collar the tongue projects inwardly and lies between the band and outer fold, thus leaving the visible surface of the band smooth. In Figs. 12 to 14, the collar band 19 is slotted to receive an end extension or tongue 20 on a separate tab 21, the tongue being offset to lie in a

different vertical plane than the body of the tab and to provide a strain-resisting shoulder 22 when the tongue is inserted through slot 20'. This tab and tongue may be cemented to opposite sides of the band as indicated at 23 on the tab and at 24 on the band, see Figs. 13 and 14.

What I claim is:

1. A celluloid collar, comprising a neck band having separate buttoning tabs affixed to its opposite ends by cement, and a supplementary self-interlocking slot and tongue connection between each tab and the corresponding end of the collar and within the

area of the cemented part thereof to provide strain relieving connections. 15

2. A celluloid collar, comprising a neck-band having a separate buttonhole tab, said tab having an integral offset portion in self-interlocking and strain-relieving connection 20 with said band, the offset portion of said tab being cemented to one side of the band and said tab being also cemented to the other side of said band in the area contiguous to said connection. 25

In testimony whereof I affix my signature.

ERNEST P. PARSONS.
